UNITED STATES PATENT OFFICE.

RUDOLPH M. GRIEBEL, OF SEATTLE, WASHINGTON.

GAME.

Application filed April 3, 1924. Serial No. 703,892.

To all whom it may concern:

Be it known that I, RUDOLPH M. GRIEBEL, a citizen of the United States of America, residing in the city of Seattle, State of Washington, have invented certain new and useful Improvements in Games, of which the following is a specification.

The invention relates to a game of skill known as "toss." It consists of a small box 10 or similar shallow flat receptacle and a ball, the box having a cup or series of cups or holes placed close together near the centre and preferably provided with means for distinguishing the cups, so that the different 15 cups or holes or groups of holes are differently scored in playing the game.

The box also is provided adjacent one corner or extremity with a socket or depression. This may be referred to as the 20 starting point or home station to receive the ball used in playing the game.

In playing, the box is grasped in a convenient manner, the ball being in the socket. The box or racket is then so manipulated or 25 vibrated as to toss the ball upward and catch it in the centre of the box, i. e., in the cup or cups, the object of the game as disclosed being to catch the ball in the cup or cups as many times out of a given number of plays, 30 i. e., tosses, as possible.

As shown, the cups are distinguished by different coloring, and the rules designate the cups of the different colors as entitling 35 the player to a different number of units to be added to his score when the ball is landed in the cups so designated. Those nearest the home station are allotted the smallest score, and the score is increased progressively, the cups which are most remote from the home station giving the highest score, though the exact arrangement and relation of score values is not essential.

In the accompanying drawing I have illustrated a game embodying the features of 45 my invention in the preferred form.

In the drawing—

Figure 1 is a plan.

Figure 2 is a section on the line 2, 2 of Figure 1, and

Figure 3 is a fragmentary section on the line 3, 3 of Figure 1.

Referring to the drawings by numerals, each of which is used to indicate the same or similar parts in the different figures, the 55 game includes a shallow box or suitable flat receptacle 1 having at or near one corner or

extremity 2 a socket or home station 3 in which I have shown a ball 4 which may be a steel ball of about seven-sixteenths of an inch in diameter, though the material and exact size are not regarded as important. The ball is, however, preferably of heavy material. The term ball is used to designate any member which may be conveniently tossed and caught in the playing of the game 60 described. Near the centre of the box I have shown a number of cups or holes 5 grouped together closely within a circular enclosure 6, though the exact arrangement of these holes is not material. They are preferably 65 close together, and the circular arrangement is desirable as providing for the most compact grouping of the holes or cups, which as shown are arranged in lines which extend transversely to the line connecting the centre 70 of the group of holes or cups with the home station.

In the form of the invention shown the line of cups 7 nearest the home are colored white. These cups are three in number. 80 The next line of cups 8 following approximately the long diameter of the circular enclosure 6 are colored green. There are four of these, and the cups 9 of the next line, of which there are three, are colored 85 red, and the cups 10 placed most remotely from the home station are colored yellow. These are two in number.

The box, as shown, also bears a schedule 11 of cup values printed on the inside of 90 the bottom near the cups, the cup values selected are as follows: white 5, green 10, red 15, yellow 20.

In the form of the invention shown the bottom of the box is also marked with the 95 representation of an arrow 12, having its butt or rear end at the socket or home station 3, and its forward end directed toward the centre of the group of holes or cups, and toward the opposite extremity of the box. 100

In using or playing the game the box is grasped in a convenient manner at a point or points remote from the home station or socket 3 which contains the ball at the beginning of each play. The ball being placed 105 in the socket is given a slight toss somewhat as though the box were a racket used in tossing a ball, and an effort is made to catch it in the cups. According to the preferred manner of playing the game as disclosed, 110 each player has five shots or tosses, and strives to make one hundred points. The

score is kept by calling aloud the number and result of each shot, the number being that of the cup in which the ball lands, and counts in the score, i. e., 5, 10, 15 or 20. 5 For instance, if the 20 hole is made at the first shot, call "20 in one"; then if a 10 or green hole is made in the second shot, the call is "30 in 2", the red hole being made in the next shot call "45 in 3". If the next 10 shot should be a miss, the call would be "45 in 4", and if at the last shot the ball should land in a white hole, the call is "50 in 5", which is the player's total score for the game. If the ball leaves the arrow base, it 15 is scored as a shot. If the ball is tossed on the cup circle but remains on the rims of the cups, the player is entitled to roll it and should attempt to score the highest number cup. The cups are closely grouped, 20 the spacing, if any, between them being preferably less than the diameter of the ball, so that when the ball lands within the group, it must enter one of the cups directly or be balanced on the rim between the cups, in 25 which instance it may be rolled into one of the cups as above described.

Having thus described a single embodiment of my invention and the manner of using the same, I would have it understood 30 that the specific description herein is for clearness and not for the purpose of limiting the protection sought, the scope of the invention being defined in the claims.

What I claim and desire to secure by Letters Patent is:

1. A game consisting of a shallow receptacle and a ball, the receptacle having a home station adapted to confine the ball at

one extremity of the receptacle, and a group of holes placed closely together, the space 40 between the holes being less than the diameter of the ball, so that when the ball lands within the group, it must enter one of said holes, the game being played by so manipulating the receptacle as to toss the ball from 45 the home station where it is initially placed, and endeavoring to catch it in the holes.

2. A game consisting of a receptacle and a ball, the receptacle having a home station adapted to confine the ball near one extremity of the receptacle, a group of holes placed closely together near the centre of the receptacle, the spacing of the holes being less than the diameter of the ball, means for 50 separately designating the different holes so that they can be conveniently scored for different amounts in playing the game, the game being played by placing the ball in the home station, so manipulating the receptacle 55 as to toss the ball, and catch it in the holes 60 which are scored as designated.

3. A game consisting of a shallow receptacle and a small heavy ball, the receptacle having a socket at one extremity as the home station for the ball and a closely arranged group of holes spaced from the home station, the game being played by 65 grasping the receptacle at a point remote from the home station, tossing the ball, and catching it in the hole.

Signed by me at Seattle, Washington, this 28th day of March, 1924.

RUDOLPH M. GRIEBEL.
